WRAPPER TRANSFER

Victor G. Hanson, Lynbrook, N. Y., assignor to
International Cigar Machinery Company, a cor-
poration of New Jersey

Application March 7, 1946, Serial No. 652,715

6 Claims. (Cl. 131—105)

1

This invention relates to cigar machines, more particularly to the wrapper transfer mechanism and wrapper-applying mechanism thereof.

One of the objects of my invention is to provide an improved operating mechanism for the wrapper carrier of the wrapper transfer. To this end it is a further object of the invention to coordinate the operation of the carrier operating mechanism and the wrapper-applying mechanism to prevent tearing or wrinkling of the wrapper applied to the cigar bunch in the wrapper-applying mechanism. For this purpose my improved carrier operating mechanism includes a novel driving mechanism which is mounted on the vertical shaft which carries an arm pivotally connected to the arm in which the wrapper carrier is revolubly mounted. Thus back-lash which is possible with the operating mechanism shown in the Wheeler Patent 2,235,857 is minimized. Moreover the wrapper-applying mechanism is driven from the carrier operating mechanism, wherefore the proper timing of the wrapper-applying mechanism and the operating mechanism will be maintained. Otherwise the wrapper may be torn or wrinkled when applied to the cigar bunch in the wrapper-applying mechanism.

Another object of the invention is to provide an improved locking mechanism comprising revoluble arms carrying locking pins operating to lock the wrapper carrier at the wrapper-receiving and wrapper-pasting positions thereof. One of these arms is rotatably adjustable to permit the wrapper carrier to be locked at different wrapper-pasting positions. In the construction shown in the Halstead Patent 2,376,355, the carrier is locked by mechanism including a block on the driven gear which is provided with a socket into which the locking pin is inserted when the wrapper carrier is at pasting position. When the wrapper pasting position of the carrier is changed the block must be unfastened from the driven gear and secured in a different position thereon corresponding to the new wrapper-pasting position of the wrapper carrier. With my locking mechanism upon adjusting said arm the carrier will be locked at the different wrapper-pasting positions obtained by an adjustment of the operating mechanism when the cams having the required cam track shapes are substituted for the stationary cams of the operating mechanism. The locking pin on the other arm will be in the required position to lock the carrier at the wrapper-receiving position, regardless of the variation in the wrapper-pasting position.

Still another object of the invention is to per-

2

mit adjustment of the carrier operating mechanism to obtain the different wrapper-pasting positions required for different shapes of cigars when cams having the required different shapes of tracks are substituted for the cams of the operating mechanism. With my novel driving mechanism this adjustment may be readily effected.

With these and other objects not specifically mentioned in view the invention consists in certain constructions and combinations which will be described and then set forth in the appended claims.

In the accompanying drawings which form a part of this specification:

Fig. 1 is a side elevation of a portion of a cigar machine equipped with my improved wrapper transfer mechanism and locking mechanism;

Fig. 2 is a plan view, viewed from line 2—2 of Fig. 1 of the portion of the cigar machine illustrated in Fig. 1;

Fig. 3 is a detail view of the locking mechanism taken from line 3—3 of Fig. 2;

Fig. 4 is a sectional view taken on the line 4—4 of Fig. 1; and

Fig. 5 is a sectional detail view taken on the line 5—5 of Fig. 2 of certain parts of the driving mechanism of the wrapper carrier operating mechanism.

Referring to Fig. 1 of the drawings it will be seen that on a table 10 is secured an upright standard 12 on whose upper end is secured one end of a plate 14. The other end of plate 14 is fastened to an upright bracket 16 which is secured to table 10. An upright shaft 20 is loosely mounted in a bearing bracket 22 fastened to the bottom of table 10 and a bearing 24 in the upper end of standard 12. The lower end of shaft 20 projects downwardly from bearing bracket 22 and has a bevel gear 26 fastened thereon. Bevel gear 26 is driven from a bevel gear 28 fastened on a drive shaft 30 to revolve shaft 20. A gear wheel 35 is provided with arcuate slots 36 shown in Fig. 2 through which pass screws 36a which clamp gear 35 to a hub 37 secured on the portion of shaft 20 projecting upwardly from bearing 24. Gear 35 meshes with and drives a gear wheel 39 in the direction indicated by the arrow in Fig. 2. Gear 39 has a hub 40 loosely mounted on a hollow vertical shaft 41. Upon loosening the screws 36a passing through the arcuate slots 36 of gear 35 the latter may be adjusted relatively to shaft 20 to obtain the correct position of gear 35 relative to gear 39.

Gear 39 has a circumferential flange 42 which

may be provided with a scale marked in degrees. The upper end of shaft 41 is supported in a bracket 43, which is fastened to plate 14, and shaft 41 projects downwardly through openings in a stationary cam 80, plate 14 and stationary cam 10. The cams 80 and 100 are secured to plate 14 and will be hereinafter more fully described.

Referring to Fig. 2, it will be seen that the gear wheel 39 has a number of spokes and that a link 47 is pivotally connected at one end to one of the spokes of gear 39 and pivotally connected at its other end by a pin 75 to a link 49. The link 49 is pivotally connected to a lug 51 on a collar 53 which is loosely mounted on a sleeve 55 keyed to the shaft 41 (Fig. 5). Above collar 53 is mounted an arm 57 having a hub secured on sleeve 55 by a set screw 58 shown in Fig. 5. Collar 53 has another lug 59 provided with an elongated slot 60 through which passes a screw 61 which is threaded into an arm 63 integral with the portion of sleeve 55 below collar 53 (see Fig. 5).

In the outer end of arm 57 is slidably mounted a vertical lock pin 65 which is urged upwardly by a compression spring mounted on pin 65 and seated on arm 57 to engage the head of pin 65 and thereby urge it upwardly. On the outer end of arm 63 is slidably mounted a vertical lock pin 70 which is urged upwardly by a compression spring 72 seated in a socket in arm 63 and engaging the head of pin 70 (Fig. 3).

The pin 75 pivotally connecting links 47 and 49 carries on its lower end a cam roller 77 engaging a cam track 79 in the cam 80.

On the lower end of the shaft 41 is clamped the hub of a hollow arm 82 which is pivotally connected to a hollow arm 84. In the outer end of arm 84 is formed a bearing in which is revolutely supported an annular hub formed on a holder 86. A wrapper carrier 88 is secured to holder 86. The wrapper carrier 88 is connected to a source of suction through the arms 82 and 84 and ports (not shown) in shaft 41. The upper end of shaft 41 is connected by a pipe 41a (Figs. 1, 2 and 5) to a suitable source of suction. Pipe 41a communicates with an opening in a plate 41b secured to bracket 43 and closing the upper end of shaft 41. Carrier 88 is provided with a perforated bottom whereby a wrapper will adhere thereto when suction is applied to the wrapper carrier. Holder 86 is retained in its bearing in arm 84 by a shaft (not shown) which is fully described in Wheeler Patent 2,215,490 and has a portion projecting upwardly from arm 84 and having secured thereon a cam piece 89 carrying a cam roller 90. On the outer end of arm 84 is formed an integral extension 92 which carries a cam roller 94. The cam rollers 90 and 94 respectively engage cam tracks 96 and 98 of the stationary cam 100. Reference may be had to the co-pending application of J. F. Halstead, S. N. 583,875, now Patent 2,471,389, for a complete disclosure of the tracks 96 and 98 and the cam piece 89. The track 96 is interrupted or non-continuous, and the track 98 has the proper contour to guide the arm 84 in a predetermined path while the track 96 swings the wrapper carrier 88 to the proper angle for applying the wrapper to the particular shape of cigar for which the cam 100 is designed. Cam piece 89 is provided with slot 102 in one end thereof and a track 104 in its outer face. At proper points intermediate the ends of track 96 the cam 100 is provided with studs on which rollers 106 and 108 are

mounted. The roller 106 enters slot 102 in piece 89 while wrapper carrier 88 is returning to its wrapper-receiving position. When roller 106 enters the slot 102 it causes the wrapper carrier 88 to make a fraction of a turn and assume the position in Fig. 4 wherein the wrapper carrier overlies the wrapper-cutting bed W and the slot 102 is about to leave roller 106 while roller 108 enters track 104. A wrapper is cut by cutting rollers (not shown) from leaf tobacco manually positioned on the die of the wrapper cutting bed before the wrapper carrier assumes the position shown in Fig. 4. The construction of the wrapper cutting bed and cutting rollers is full described in Wheeler Patents 2,215,490, 2,316,828 and 2,343,946. When the suction head L of the wrapper cutting bed is raised to transfer the cut wrapper to the wrapper carrier 88 (Fig. 1) while the latter dwells over the wrapper cutting bed, the suction on the suction head L is cut off and suction applied to the wrapper carrier at the moment the wrapper contacts the bottom of the wrapper carrier. Thus the wrapper will adhere to the wrapper carrier bottom and the carrier will be moved to a wrapper-pasting position indicated in dotted lines in Fig. 4 at which paste is applied to the flag end of the wrapper by a paster device P of conventional construction. The tuck end of the pasted wrapper is then stripped from the carrier by a tuck needle T of conventional construction which enters a notch 110 in the wrapper carrier (Fig. 1) and presses the tuck end of the wrapper against the tuck end of a cigar bunch (not shown) revolving in the wrapper-applying mechanism M to cause the wrapper to be spirally wound about said cigar bunch.

It will be understood that the shaft 41 will turn at different speeds at different positions of the carrier in each cycle of the machine and that the movement of the wrapper carrier is cyclically interrupted at the wrapper-receiving and wrapper-pasting positions. For this purpose the track 79 of cam 80 has a predetermined configuration to displace the cam roller 77, while the carrier is at wrapper-receiving and pasting positions, and thereby cause the link 49 to turn the collar 53 with the shaft 41 in a direction opposite to the direction in which the shaft 41 is being turned due to the connection of link 47 to a spoke of gear wheel 39, and at a speed sufficient to cause the rotation of shaft 41 to be interrupted while the wrapper carrier is at wrapper-receiving and pasting positions. For this purpose the cam track 79 is provided with sections 79a and 79b (Fig. 2) which are concentric with the center of the pin connecting the link 49 to the lug 51 of collar 53. Cam track sections 79a and 79b thus have the shape required to produce a dwell in the motion of the wrapper carrier 88 at the wrapper-receiving and wrapper-pasting positions thereof. Thus the wrapper carrier will remain stationary at these two positions.

The track 79 of cam 80 is also provided with eccentric portions 79c, 79d and 79e which cause the cam roller 77 to displace link 49 and turn the collar 53 and thereby turn the shaft 41 to advance or retard the speed of rotation of shaft 41 relative to the rotation of gear 39, as required at different positions of the wrapper carrier. At sections 79a and 79b of the track 79, where the speed of the reverse motion of shaft 41 is equal to the angular velocity of the forward motion of gear 39, the shaft 41 will re-

main stationary. It will be understood that the shape of track 79 shown in Fig. 2 is suitable for one shape of cigar.

While the wrapper carrier 88 dwells at wrapper-receiving position its tuck end is at the right of Fig. 2. Then when the wrapper carrier resumes its motion the roller 108, which entered track 104 of cam piece 89 as roller 106 left slot 102 thereof, passes through track 104 and the cam piece 89 is turned to cause the tuck end of the wrapper carrier to be swung inwardly and the roller 90 enters the adjoining end of track 96. The roller 90 is then guided by track 96 whose contour is such that the wrapper carrier will be turned to the proper position while it is moved in a predetermined path for pasting the flag end of the wrapper and insertion of its tuck end in the wrapper-applying mechanism M. The continued engagement of roller 90 with track 96 then causes the wrapper carrier to assume the proper angles for application of the wrapper to the particular shape of cigar for which cam 100 is designed. The wrapper carrier subsequently returns to a position wherein its slot 102 engages the roller 106 and causes the carrier to assume its wrapper-receiving position after the position of the wrapper carrier is reversed when the roller 90 leaves the track 96.

When the wrapper carrier reaches its wrapper-receiving position, the locking pin 70 on arm 63 assumes a position overlying a hole 150 in cam 80 and the pin is moved downwardly by mechanism which will now be described, into hole 150 to lock the wrapper-carrier in said position. For this purpose a lever 152 is fulcrumed on a bracket 154 secured to plate 14 and arm 152 has a grooved lug 156 into the groove of which the head of pin 70 enters when it moves along to a position above hole 150. On the upper face of gear 39 is secured a cam block 158 which engages a cam roller 160 on an arm 162 of lever 152 as the wrapper carrier approaches wrapper-receiving position. The cam roller 160 is urged towards the upper face of gear 39 by a tension spring 164 connected to lever 152 and bracket 154. In a lug of lever 152 is threaded a stop-screw 166 which engages bracket 154 whereby the position of cam roller 160 may be regulated by turning screw 166. The cam-block 158 has an inclined face on the upper edge of its leading end which serves to lift the cam roller 160 and displace arm 152 into a position wherein the groove in lug 156 of lever 152 is aligned with the head of pin 70 as the latter moves to a position above hole 150. The inclined face of block 158 merges into a horizontal face which supports the roller 160 at the position required to maintain the groove in lug 156 in a position aligned with the head of pin 70 while the latter enters said groove. The roller 160 then drops into a recess 158a of block 158 as the wrapper carrier assumes its wrapper-receiving position whereby the pin 70 is depressed sufficiently to enter the hole 150 and thereby lock the wrapper carrier while it dwells at wrapper-receiving position. The trailing end of recess 158a serves to lift the roller 160 and thereby withdraw pin 70 from hole 150 when the wrapper carrier resumes its motion. Behind the recess 158a is a horizontal face which serves to support the head of pin 70 in an elevated position while said head moves out of the groove of lug 156 after the pin is withdrawn from hole 150. The roller 160 then engages an inclined face on the trailing end of cam block 158

whereby the lever 152 is returned to a position determined by the setting of screw 166.

On the upper face of gear 39 is also secured a cam block 159 which has a configuration similar to block 158 and properly spaced therefrom to cause the pin 65 to be inserted into the hole 150 while the wrapper carrier dwells at wrapper-pasting position, and then withdrawn when the carrier resumes its motion.

In order to vary the wrapper-pasting position of the wrapper carrier when the wrapper is to be applied to a different shape of cigar, cams 80 and 100 are replaced by cams having the required different shapes of cam tracks, the screw 61 passing through slot 60 of lug 59 is loosened and the collar 53 is manually turned to a different predetermined position relative to arm 63. The screw is then tightened again to clamp lug 59 against arm 63.

When the lug 59 is turned in one direction relatively to arm 63, after loosening screw 61, until the latter engages one end of the slot 60 the wrapper carrier will be moved to a pasting position required for a tapered tuck end cigar. Thus cigars having tapered tuck ends can be wrapped upon making this adjustment and replacing cams 80 and 100 with cams having tracks designed for this shape of cigar. Upon moving the lug 59 relatively to arm 63 to engage the other end of slot 60 with screw 61 the wrapper carrier will be moved to the proper pasting position for a blunt tuck end cigar if cams 80 and 100 are replaced by cams whose tracks have the proper shape for this type of cigar. Intermediate shapes of cigars can be handled by adjusting lug 59 relatively to arm 63 to a position intermediate these two extreme positions if the cams 80 and 100 are replaced by cams having the required shape of track for each different shape of cigar. When the lug 59 is adjusted to vary the wrapper-pasting position of the carrier the set screw securing the hub of arm 57 to collar 55 (Fig. 5) should be loosened and arm 57 turned to the proper position to overlie hole 150 in cam 80 when the carrier dwells at pasting position. Thus the locking pin 65 will be inserted by the arm 152 into hole 150 while the carrier dwells at wrapper-pasting position.

One convenient way of adjusting the lug 59 to the proper position relatively to arm 63 to obtain the desired different wrapper-pasting position after screw 61 is loosened and cams 80 and 100 have been replaced by cams having the required shape of tracks, is to manually move the cam roller 75 into the section of the cam track of the new cam 80 which causes the wrapper carrier to dwell at wrapper-receiving position. The lug 59 will thus be turned to the required position. When the wrapper carrier is then moved to the wrapper-pasting position it will have the required different position. Alternatively the cam roller 75 may be manually moved to the section of the track of the new cam 80 which causes the wrapper carrier to dwell at pasting position. The lug 59 will thus be moved to the required position. After adjustment in either manner the screw 61 is tightened. It will be understood that the arm 63 will remain in the same position while the wrapper-pasting position of the carrier is adjusted. Thus the pin 70 will be inserted into hole 150 to lock the carrier at wrapper-receiving position regardless of variations in the pasting position thereof.

On the portion of shaft 20 within standard 12 is fastened a bevel gear 200 which drives a bevel

gear 202. Gear 202 is connected through a separable coupling 204 with the drive shaft 206 of wrapper-applying mechanism M whose construction is fully described in the Durning Patent 2,290,171. Thus the wrapper-applying mechanism is directly driven from the shaft 12 in timed relation to the operation of the wrapper transfer mechanism.

It may be observed that when the wrapper carrier is locked at wrapper-pasting position while the needle T is being inserted into the notch 110 in the wrapper carrier, there is no possibility of the carrier being displaced. Therefore there is no possibility of breaking the needle, as is the case when the carrier is not locked at this position.

It should be mentioned that suitable mechanism for operating the needle T is shown and described in the above-mentioned Durning Patent 2,290,171 and also in the Clausen Patent 2,281,095. For further disclosure of a suitable type of paster mechanism for applying paste to the flag end of the wrapper on the carrier, reference may be had to the Shedlock Patent 863,106.

In the operation of my wrapper transfer the wrapper carrier 88 dwells at the wrapper-receiving position shown in the drawings while the wrapper is delivered thereto from the suction head L of the wrapper-cutting bed W. The wrapper is suctionally retained on the bottom of the wrapper carrier, when the shaft 41 resumes its rotation. The wrapper is thus transported to the wrapper-pasting position. At this position of the wrapper carrier its movement is again interrupted while the rotation of the shaft 41 is stopped, and paste is applied by the device P to the head end of the wrapper adhering to the wrapper carrier. The tuck end of said wrapper is removed from the wrapper carrier by the tuck needle T and pressed against the tuck end of the cigar bunch in the wrapper-applying mechanism M. The wrapper carrier then resumes its motion and the remainder of the wrapper is removed therefrom and wound spirally about the revolving cigar bunch in the wrapper-applying mechanism M. After the wrapper is applied to said cigar bunch the wrapper carrier returns to the wrapper-receiving position at which it dwells to receive another wrapper from the suction head L of the wrapper-cutting bed W.

While the wrapper carrier dwells at the wrapper-receiving position the locking pin 70 is inserted in the hole 150 of cam 80 to prevent rotation of shaft 41 and thereby prevent movement of the wrapper carrier at this position. When the wrapper carrier dwells at wrapper-pasting position the locking pin 65 is inserted into hole 150 to prevent movement of the wrapper carrier.

What is claimed is:

1. In a cigar machine having mechanism for applying a wrapper to a cigar bunch, the combination with a wrapper carrier adapted to support a wrapper, of means for moving said carrier from a wrapper-receiving position to a wrapper-pasting position adjacent said wrapper-applying mechanism and then returning said carrier to wrapper-receiving position through a predetermined path along said wrapper-applying mechanism to permit application of the wrapper on said carrier to a cigar bunch in said wrapper-applying mechanism, said carrier moving means operating to stop said carrier momentarily at said wrapper-receiving and wrapper-pasting positions and including a rotatable member to which said carrier is connected, and a device for

locking said carrier at said wrapper-receiving position and at said wrapper-pasting position, said locking device including a pair of arms rigidly connected to said rotatable member and movable therewith, detents carried by said arms to be successively moved to a predetermined position while said carrier dwells at wrapper-receiving and wrapper-pasting positions, a stationary member provided with a recess arranged to underlie each of said detents successively while said carrier dwells at said wrapper-receiving position and at wrapper-pasting position, and instrumentalities for inserting each of said detents successively into said recess while said carrier dwells at wrapper-receiving and wrapper-pasting positions.

2. In a cigar machine having mechanism for applying a wrapper to a cigar bunch, the combination with a wrapper carrier adapted to support a wrapper, of means for moving said carrier from a wrapper-receiving position to a wrapper-pasting position adjacent said wrapper-applying mechanism and then returning said carrier to wrapper-receiving position through a predetermined path along said wrapper-applying mechanism to permit application of the wrapper on said carrier to a cigar bunch in said wrapper-applying mechanism, said carrier moving means operating to stop said carrier momentarily at said wrapper-receiving position and said wrapper-pasting position, and said carrier moving means including a vertical shaft, a primary arm fastened on said shaft and a secondary arm connected to said primary arm, said carrier being mounted in said secondary arm, and a driving mechanism connected to said shaft, said driving mechanism including a stationary cam, a link engaging said cam, a sleeve attached to said shaft, a collar loosely mounted on said sleeve, means attaching said collar to said sleeve in a predetermined adjusted position to permit variation of the wrapper-pasting position of said carrier, and a link connecting said first-named link to said collar.

3. In a cigar machine having mechanism for applying a wrapper to a cigar bunch, the combination with a wrapper carrier adapted to support a wrapper, of means for moving said carrier from a wrapper-receiving position to a wrapper-pasting position adjacent said wrapper-applying mechanism and then returning said carrier to wrapper-receiving position through a predetermined path along said wrapper-applying mechanism to permit application of the wrapper on said carrier to a cigar bunch in said wrapper-applying mechanism, said means operating to stop said carrier momentarily at said wrapper-receiving position and said wrapper-pasting position, said carrier moving means including a vertical shaft, a primary arm fastened on said shaft and a secondary arm connected to said primary arm, said carrier being mounted in said secondary arm, a driven member mounted on said shaft, and a driving mechanism connected to said driven member, said driving mechanism including a stationary cam, a rotating driving member concentric with said shaft, a primary link pivotally connected to said driving member, a secondary link pivotally connected to said driven member, a pin pivotally connecting said links, and a cam follower on said pin, said cam having a cam track engaging said cam follower, and said cam track having a configuration adapted to interrupt the rotation of said driven member and thereby momentarily stop the rotation of said shaft and cause said car-

rier to dwell at the wrapper-receiving position and at the wrapper-pasting position thereof.

4. In a cigar machine having mechanism for applying a wrapper to a cigar bunch, the combination with a wrapper carrier adapted to support a wrapper, of means for moving said carrier from a wrapper-receiving position to a wrapper-pasting position adjacent said wrapper-applying mechanism and then returning said carrier to wrapper-receiving position through a predetermined path along said wrapper-applying mechanism to permit application of the wrapper on said carrier to a cigar bunch in said wrapper-applying mechanism, said means operating to stop said carrier momentarily at said wrapper-receiving position and said wrapper-pasting position, said carrier moving means including a vertical shaft, driven mechanism including a driven member mounted on said shaft, and a driving mechanism connected to said driven member, said driving mechanism including a stationary cam, a rotating driving member concentric with said shaft, a primary link pivotally connected to said driving member, a secondary link pivotally connected to said driven member and primary link, said driven member being rotatably adjustable relative to said shaft and having a lug provided with an elongated slot, and said driven mechanism also including a connecting member rigidly connected to said shaft, and a screw passing through said slot and threaded into said connecting member to rigidly connect said driven member to said connecting member and thereby revolve said shaft with said driven member whereby upon loosening said screw said driven member may be turned for adjustment relative to said connecting member.

5. In a cigar machine having mechanism for applying a wrapper to a cigar bunch, the combination with a wrapper carrier adapted to support a wrapper, of means for moving said carrier from a wrapper-receiving position to a wrapper-pasting position adjacent said wrapper-applying mechanism and then returning said carrier to wrapper-receiving position through a predetermined path along said wrapper-applying mechanism to permit application of the wrapper on said carrier to a cigar bunch in said wrapper-applying mechanism, said means operating to stop said carrier momentarily at said wrapper-receiving position and said wrapper-pasting position, said carrier moving means including a vertical shaft, a primary arm fastened on said shaft and a secondary arm connected to said primary arm, said carrier being mounted in said secondary arm, a driven member mounted on said shaft, a driving mechanism connected to said driven member, and a continuously rotating driving

member concentric with said shaft and connected to said driving mechanism to revolve said shaft.

6. In a cigar machine having mechanism for applying a wrapper to a cigar bunch, the combination with a wrapper carrier adapted to support a wrapper, of means for moving said wrapper carrier from a wrapper-receiving position to a wrapper-pasting position adjacent said wrapper-applying mechanism and then returning said carrier to wrapper-receiving position, said means operating to stop said carrier momentarily at said wrapper-receiving and wrapper-pasting positions and then return said carrier to wrapper-receiving position through a predetermined path along said wrapper-applying mechanism to permit application of the wrapper on said carrier to a cigar bunch in said mechanism, said carrier moving means including a vertical shaft, a primary arm connected to said shaft, a secondary arm pivotally connected to said primary arm, said carrier being mounted in said secondary arm, and a driving mechanism for revolving said shaft, said driving mechanism including a continuously revolving member, a primary link pivotally connected to said continuously revolving member, a secondary link, a pin pivotally connecting said primary and secondary links, a driven member pivotally connected to said secondary link and driving said shaft, a cam follower on said pin, and a stationary cam having a cam track engaging said cam follower, said track having a predetermined configuration to interrupt the rotation of said driven member and thereby stop said carrier momentarily at wrapper-receiving position and at wrapper-pasting position.
